UNITED STATES PATENT OFFICE.

WILLIAM FROHNE, OF CINCINNATI, OHIO.

MOP-WRINGER.

1,210,059.

Specification of Letters Patent. Patented Dec. 26, 1916.

Application filed August 30, 1916. Serial No. 117,798.

To all whom it may concern:

Be it known that I, WILLIAM FROHNE, a citizen of the United States, and a resident of Cincinnati, in the county of Hamilton and State of Ohio, have invented certain new and useful Improvements in Mop-Wringers, of which the following is a full, clear, and exact description, reference being had to the accompanying drawings, forming 10 a part of this specification.

My invention relates to vessels and mop-wringing apparatus connected therewith, and the object of said invention is to provide a device of said character of simplified and 15 efficient construction to the end that the same may be manufactured at a minimum cost and at the same time be of increased efficiency in operation.

In the several figures of the drawings, 20 like numerals indicate like parts.

In the drawings: Figure 1 is a side elevation of my new mop-wringer. Fig. 2 is a plan of the same. Fig. 3 is a central longitudinal section of said device. Fig. 4 is a 25 detail in perspective of one of the mop-wringing rollers and the mountings thereof. Fig. 5 is a similar view of the coöperating roller. Fig. 6 is a perspective of one of the pivotal mountings of the roller supports.

30 The numeral 1 indicates a vessel. The said vessel may be made of any suitable material, the preferred material being sheet metal galvanized. The shape of said vessel is preferably rectangular as shown in the drawings. The said vessel is provided with a handle 2 pivotally mounted so that the same may be dropped to the side of the vessel when not in use. Riveted to the ends of said vessel at suitable points are pivotal supports 3 and 4, the supports 3 at one end being slightly below the middle depth of the vessel and the supports 4 at the other end near the top thereof. The said supports 40 are so mounted in the vessel that the pins 5 thereof abut against the adjacent sides of the vessel. Pivotally mounted on the pins 5 of supports 3 are plates 6 and 7, the same being constructed of metal similar to that used in the construction of the vessel 1. 45 Journaled in the front ends of plates 6 and 7, slightly below the upper edges thereof, is a roller 8. Mounted between the plates 6 and 7 to the rear of the roller and sloping upwardly therefrom is a tread board 9, the 55 plates 6 and 7 being provided with rear-

wardly extending portions 10 to provide for the mounting of said tread. At the front end of said tread is a baffle 11. Pivotally mounted on the pins of supports 4 are plates 12 and 13 between which a roller 14 60 is journaled.

To provide an operative connection between the mountings of rollers 8 and 14, the ends 15 of rollers 8 mounted between the plates 6 and 7 project slightly beyond 65 said plates and extend through curved slots 16 in the plates 12 and 13, the distance between said plates 6 and 7 being slightly less than that between plates 12 and 13, thereby permitting the former pair to lie 70 and operate between the latter pair, the ends 15 reciprocating in the slots 16.

The operation of my device will be apparent to those skilled in the art to which the same appertains from the foregoing description.

To open the rollers, the operator places one foot upon the tread 9 bearing downwardly and backwardly thereon, so that the roller 8 is rocked into the position 80 shown in full lines in Fig. 3. The roller 8 is thus raised and brought back, the ends 15 thereof operating in the slots 16 in the plates 12 and 13, thereby producing an opposite rocking of the roller 14, so that the 85 said rollers are separated for the introduction of a mop. To wring the mop when introduced between the rollers, the foot is pressed downwardly and forwardly upon the tread 9, forcing the roller 8 in a corresponding direction. The ends 15 of the roller 8 again operating in the slots 16 carry the roller 14 into cooperating position so that when the mop is withdrawn between them, the said rollers compress the same. 95

Having thus described my invention, what I claim as new and desire to secure by Letters Patent is:

A device of the character specified comprising a vessel, plates pivotally mounted 100 near one end of said vessel, a roller journaled between said plates, plates pivotally mounted near the opposite end of said vessel, a second roller journaled between said plates, means for the rocking of said 105 first roller, and means, upon the rocking of said first roller, whereby said second roller may be oppositely actuated, substantially as and for the purpose described.

WILLIAM FROHNE.
